UNITED STATES PATENT OFFICE.

JOHN L. COLES AND DAVID H. COLES, OF BROOKLYN, ASSIGNORS TO THE
EMPIRE STATE MANUFACTURING COMPANY, OF NEW YORK, N. Y.

PARALLEL JAW-TOOL.

SPECIFICATION forming part of Letters Patent No. 424,274, dated March 25, 1890.

Application filed June 6, 1889. Serial No. 313,352. (No model.)

To all whom it may concern:

Be it known that we, JOHN L. COLES and DAVID H. COLES, both citizens of the United States, residing at Brooklyn, in the county of Kings and State of New York, have invented new and useful Improvements in Parallel Jaw-Tools, of which the following is a specification.

This invention relates to a parallel jaw-tool which shall be capable of easy operation and adjustment; and the invention consists in the details of construction set forth in the following specification and claims, and illustrated in the accompanying drawings, in which—

Figure 1 is a side elevation of a parallel jaw-tool. Fig. 2 is a plan view of Fig. 1. Fig. 3 is a detail view of a bracket. Fig. 4 is a detail sectional elevation showing the inner side of a bracket. Fig. 5 is a detail view of a fulcrum. Fig. 6 is a section along line $x-x$, Fig. 1. Fig. 7 shows a tool secured to a jaw.

Similar letters indicate corresponding parts. In the drawings, the letter A indicates a rigid or fixed jaw having a handle B and provided with a slotted bracket. The bracket can be readily composed of two cheek-pieces C C, fixed to the jaw A by riveting, welding, or by being formed integral with the jaw. The bracket has a way or guides D D for the fulcrum E of the jaw F. The jaw F, as seen in Fig. 1, is made to pass more than half-way about the fulcrum E, so that said jaw is secured to the fulcrum and moves with the fulcrum as the fulcrum is adjusted back and forth along the way D. A nut H, engaging the screw I, serves to adjust the fulcrums along the way D. The nut H is held in place by a support K, which is secured to the bracket C C in any suitable way, as by riveting, doweling, soldering, or screwing. The movable jaw F has a handle G. The fulcrum E can be adjusted so that the jaw F will be at such a distance from the jaw A that only a slight movement of the jaw F is required to enable a nut or other object to be grasped between the jaws A F, so that the jaws A F can be left practically parallel to one another during the operation of the tool. The handle G is made to move in a slot L in the handle B, whereby the handle G is prevented from moving laterally.

The jaws A F can be used for various purposes, such as to grasp nuts or bolts or to support various tools—such as belt-punches, 55 shears, snips, various-shaped pincher-jaws, pliers, and other tools—which may be readily secured to or taken from the jaws A F. The parallelism of the jaws and the adjustability of the jaws toward and from one another will 60 insure accurate relative position of the tool parts—as, for example, of the male and female parts of a punch.

In Fig. 7 a punch is shown secured to a jaw. By beveling the jaw and making the engaging portion of the tool in dovetail shape the tool can be readily slipped onto the jaw.

What we claim as new, and desire to secure by Letters Patent, is—

1. A parallel jaw-tool consisting of a rigid 70 jaw A, having a handle B and a slotted bracket provided with guides D, a support K on the end of the bracket, a rotating nut H between the support and the bracket, an adjustable screw I, passing through the support and nut 75 and formed at its inner end with a fulcrum E, and a jaw F, journaled and swinging on the fulcrum on the inner end of the screw and having a handle G, disconnected from the handle of the rigid jaw, substantially as 80 described.

2. A parallel jaw-tool adapted for the male and female parts of a punch, consisting of a rigid jaw A, having a handle B, provided with a slot L, and a slotted bracket provided with 85 guides D, a support K on the end of the bracket, a rotating nut H between the support and the bracket, a screw I, passing through the support and nut and formed at its inner end with a fulcrum E, and a jaw F, 90 journaled and swinging on the fulcrum on the inner end of the screw, and having a handle passing through and disconnected from the slotted part of the handle on the rigid jaw, substantially as described. 95

In testimony whereof we have hereunto set our hands in the presence of two subscribing witnesses.

JOHN L. COLES.
DAVID H. COLES.

Witnesses:

WILLIAM C. HAUFF,
ERNST F. KASTENHUBER.

Correction in Letters Patent No. 424,274.

It is hereby certified that the assignee, "The Empire State Manufacturing Company," in Letters Patent No. 424,274, granted March 25, 1890, upon the application of John L. Coles and David H. Coles, of Brooklyn, New York, for an improvement in "Parallel-Jaw Tools," should have been described and specified as *The Empire State Manufacturing Company, a corporation organized under the laws of the State of New Jersey, and doing business at Jersey City, N. J., and New York, N. Y.*; and that the said Letters Patent should be read with this correction therein that the same may conform to the record of the case in the Patent Office.

Signed, countersigned, and sealed this 1st day of April, A. D. 1890.

[SEAL.]

CYRUS BUSSEY,
Assistant Secretary of the Interior.

Countersigned:

C. E. MITCHELL,

Commissioner of Patents.
